FORGING MACHINE

Wade H. Wineman, Michigan City, Ind., assignor
to Sullivan Machinery Company, a corporation
of Massachusetts

Original application June 11, 1931, Serial No.
543,635. Divided and this application November
22, 1932, Serial No. 643,868

33 Claims. (Cl. 76—5)

My invention relates to clamping mechanisms, and more particularly to clamping mechanisms particularly useful in the sharpening of drill steels. Such clamping mechanisms commonly 5 form part of forging machines, and the latter are used not only in blacksmith or forge shops, but also in contract work such as road building or the like; and it is therefore highly desirable that they be readily transportable, and therefore that 10 all their parts be of light weight. Provision of mechanism which shall not require a pressure fluid operating motor for clamp operation, provided adequate clamping pressure can be attained without excessive weight, is desirable; but 15 of course it is necessary that the clamping devices be adapted for the rigid holding of the drill steels upon which work is to be performed during certain operations.

It is a primary object of my invention to provide an improved clamping mechanism. A more particular object of the invention is to provide an improved drill sharpener having an improved clamping mechanism whereby through simple man-power operated mechanism a very rigid 25 clamping can be effected. Other objects and advantages of the invention will become apparent as the description proceeds and the several objects are attained by the organization and details of construction hereinafter more fully described.

In the accompanying drawings, I have shown for purposes of illustration one embodiment of the invention, and in these drawings,—

Fig. 1 is a side elevation of the illustrative embodiment of the improved clamping mechanism embodied in a drill sharpener.

Fig. 2 is a front elevation thereof.

Fig. 3 is an approximately central section taken on the plane of the line 3—3 of Fig. 2.

Fig. 4 is a horizontal section on the plane of the line 4—4 of Fig. 2.

Fig. 5 is a detail sectional view on the broken line 5—5 of Fig. 1, showing a detail of the clamp operating mechanism.

Fig. 6 is a plan view of the upper clamp jaw.

This application is a division of my co-pending application, Serial No. 543,635, filed June 11, 1931.

The illustrative embodiment of my invention 50 is incorporated in a mechanism which comprises a main frame 1 supporting a clamping or vise mechanism 2, a gauging mechanism 3, an upsetting mechanism 4, and a swaging mechanism 5.

The main frame 1 of the machine is conveniently formed as a casting and comprises a top

portion 10, a pair of lateral leg portions 11 and a base portion 12. The base portion 12 has secured thereto, as by bolts 14, a pair of foot members 15 serving to provide a more extended contact with the surface upon which the machine 5 is supported.

The top portion 10 of the frame member 1 is provided with a suitably formed recess 17 for the reception of a lower clamping die 18. At one side, the portion 10 has an upstanding ear 10 member 19 supporting a pin 20 which forms a pivot for the upper clamping die or vise jaw 21, the latter having ear portions 22 at opposite sides of the ear 19. A suitably formed recess 23 in the upper vise jaw 21 supports an upper 15 clamping die or vise jaw 24. The lower clamping die is held in position longitudinally of the machine by a pin 25 receivable in a recess 26 in the portion 10 of the main frame and is held against upward movement from its seat by a die 20 retaining pin 27. The upper clamping die or vise jaw is held in position by a stud 28 passing through an opening 29.

The upper vise jaw 21 is movable angularly 25 about the pivot pin 20 toward and from clamping position, and it receives its movement toward clamping position from two different devices. Both of these devices are operable by a lever 31 which is of the bell crank shape and is pivoted at the end of its short arm on the frame at 32. 30 The lever is connected at the juncture of its arms at 33 to a member 34 which comprises a body portion 35 and an angularly extending arm 36. At its outer end at 37 the arm 36 is pivotally connected to a vertically extending link member 38. The upper end of the link member 38 is pivotally connected at 39 to the upper vise jaw 21. It will be apparent that as the lever 31, which has a foot rest 40 thereon, swings counterclockwise about the pivot 32, a small angular 40 movement will result in a substantial upward movement of the pivot point 37, with a resulting material opening movement of the upper clamping jaw 21. A spring 42 connected between a pin 43 on the frame and an opening 44 in the link 45 38, and a spring 42^a connected between a pin 43^a on the frame and a pin 44^a on the member 34, normally tend to maintain the lever 31 in raised position and the clamping jaw 21 open. Adjacent the upper side of the body 35 of the lever 50 member 34 is a split threaded clamp 46 in which a rod 47 is rigidly secured. This rod at its upper end is formed with an eye 48 in which a pin 49 is mounted, the opposite ends of the pin supporting a cam lever 50 which is adapted to en- 55

gage seats 51 at opposite sides of a slot 52 opening through the back side of the clamping jaw member 21. It will be understood that when the cam lever 50 is thrown rearwardly, the rod 5 47 can be moved backwardly about its pivotal connection 33 with the bell crank, out of the slot 52, and permitted to engage a rest 53 suitably supported at the rear end of the machine, and there be supported. With the rod withdrawn 10 thus from cooperation with the vise jaw 21, the spring 42 will act upon the link 38 and open the vise jaw.

The clamping operation may now be briefly described. A steel to be clamped between the dies 18 and 24 is properly positioned upon the lower die, and the operator then depresses the lever 31 with his foot, which moves the upper clamping jaw 21 angularly about its pivot 20 to closed position. When substantially closed position is reached, the operator takes hold of the cam lever 50 and moves the same together with the rod 41 forwardly until the lever 50 overlies the surfaces 51. During such movement it will be noted that the operating rod 41 swings about 25 an axis making a substantial angle with a line parallel to the jaw pivot axis, from a position outside the path of pivotal movement of said jaw to a position in the slot 52. Prior to such movement, the cam lever 50 lies outside the plane 30 of jaw movement, and the swinging movement of the rod brings the cam lever 50 into the vertical plane of movement of the jaw and its supporting means. The cam lever 50 is then moved angularly about the pin 49, and a clamping engagement is effected. Then by stepping on the foot plate 40 on the lever 31, the final clamping pressure will be imparted to the steel held between the dies 18 and 24, a very powerful clamping action being secured, due to the fact that 35 the pivot 33 lies almost directly below the pivot 32 with the result that a very great amount of pressure can be transmitted to the bit due to the fact that the mechanical advantage is very great. 40

45 great. Gauging of finished bits is effected between an upper gauging die 55 and a lower adjustable gauging die 56. The upper die is carried by the pivoted upper clamping jaw 21, while the lower is mounted in a recess 57 in the frame and is vertically adjusted in that recess by a screw 58 with whose polygonal head 59 a suitable angle clamp 60 cooperates. Obviously a gauging pressure is applied to the bit to be gauged, in substantially the same manner that the clamping pressure is applied, as just explained.

The upsetting mechanism 4 is supported in alignment with the clamping dies 18 and 24, and its construction and mode of operation are fully described in my co-pending application Serial No. 543,635, above mentioned.

It will suffice, for this present application, to state that when a bit to be upset has been clamped between the dies 18 and 24, a motor 62 supplied with motive fluid under control of a valve 67, will percussively actuate a suitable dolly 70 and effect the necessary upsetting and shaping operation on the end of the drill steel.

The swaging mechanism 5 is also fully described in my co-pending application Serial No. 543,635, above mentioned. For the present application, it is sufficient to state that it comprises an upper die 12 held in position in the main frame 1, and a lower die 15 vertically reciprocable in the frame 1, there being a vertical ham-

mer motor 77 for actuating the lower die after suitably positioning it.

When it is desired to swage a steel, it will be placed in suitable position against the upper stationary swaging die 72, the lower swaging die 75 and its actuating motor will be moved upwardly, and the motor will be supplied with fluid to cause its operation.

It will be noted that the present mechanism is a very simple one, that no air is consumed in the operation of the clamping and gauging devices, and thus the relatively large consumption of air which is encountered with some drill sharpening mechanisms in the operation of the clamping devices is avoided, but that by reason of the great mechanical advantage of the present clamping mechanism drill steels may be securely held and adequately gauged by forces within the power of the operator himself. It will be noted, moreover, that the entire mechanism is light but rugged, that it may be readily transported from one job to another, and that it can easily be set up at any desired point of use.

desired point of use. While there is in this application specifically described one form which the invention may assume in practice, it will be understood that this form of the same is shown for purposes of illustration and that the invention may be modified and embodied in various other forms without departing from its spirit or the scope of the appended claims. 25 30

What I claim as new and desire to secure by Letters Patent is:

Letters 1-1
1. In a forging machine, a clamping member, a cooperating pivoted clamping member, and means for effecting clamping operation of said pivoted clamping member including means for transmitting a clamping force thereto cooperating therewith at a point spaced from its axis of pivotal movement and cooperating clamping means associated with an element of said first mentioned means and actuated thereby. 35 40

2. In a forging machine, a stationary clamping die, a pivoted clamping member carrying a clamping die arranged to cooperate in one position of said pivoted clamping member with said stationary die, and means for effecting clamping movement of said pivoted clamping member cooperating with the latter at a point thereon at the opposite side of the clamping die carried thereby from the axis of pivotal movement and cooperating clamping means associated with an element of said first mentioned means and actuated thereby. 45 50 55

3. In a forging machine, a stationary clamping die, a pivoted clamping member carrying a clamping die arranged to cooperate in one position of said pivoted clamping member with said stationary die, and a plurality of means for effecting closure of said clamping dies and for only thereafter imparting a final clamping pressure thereto both cooperating with the pivoted clamping member at the opposite side of the clamping die thereon from the axis of pivotal movement, said final clamping means operated by an element of said closure effecting means. 55 60 65

4. In a forging machine, a clamping device including a pivoted clamping member having a pivotal support at one end and a clamping die between said pivotal support and the other end thereof, and a plurality of positioning and final clamping force applying means cooperating with the last mentioned end of said clamping member and operative to first position the clamping 75

die and only thereafter to apply a final clamping pressure thereto, said final clamping means operated by an element of said positioning means.

5. In a forging machine, a clamping device including a pivoted clamping member carrying a vise jaw, means permanently connected with said clamping member for moving said vise jaw between open and substantially closed positions, and tension means detachably connected with 10 said clamping member and tensionable from the side of said clamping member at which said vise jaw moving means is disposed for applying a final clamping force to said vise jaw after the same has been moved to substantially closed position 15 by said first mentioned means.

6. In a forging machine, a clamping device including a pivoted clamping member carrying a vise jaw, means permanently connected with said clamping member for moving said vise jaw between open and substantially closed position, and tension means spaced from the jaw when the latter is open and connectible with said jaw only after substantial closure thereof, for drawing said 20 jaw with increased clamping force into clamping 25 position.

7. In a forging machine, a clamping device including a movable clamp jaw and means for opening and closing said jaw and causing said jaw to exert a clamping pressure including a common primary element to which force is applicable, and a plurality of cooperating jaw actuating devices each actuated by said element and one operative to open and close said clamp jaw and another operative to apply a final clamping pressure thereto.

8. In a forging machine, a clamping device including a movable clamp jaw and means for opening and closing said jaw and causing said jaw to exert a clamping pressure including a common primary element to which force is applicable and devices each actuated by said element respectively for opening and closing said clamp jaw and for applying a final clamping pressure thereto, one of said devices having a constant operative connection with said clamp jaw and the other an intermittent operative connection therewith.

9. In a forging machine, a clamping device including a movable clamp jaw and means for opening and closing said jaw and causing said jaw to exert a clamping pressure including a common primary element to which force is applicable and devices each actuated by said element respectively for opening and closing said clamp jaw and for applying a final clamping pressure thereto, the first of said devices having a constant operative connection with said clamp jaw and the other an intermittent operative connection therewith.

10. In a forging machine, a clamping device including a movable clamp jaw having supporting means, and means for imparting a clamping pressure to said jaw through said supporting means having a bodily detachable connection with the latter enabling releasing of said clamping pressure imparting means from said clamp jaw supporting means at will, said connection completely disengagable therefrom and removable out of the plane of movement of said jaw and its supporting means during the complete opening of said jaw.

11. In a forging machine, a clamping device including a movable clamp jaw, means for imparting a clamping pressure thereto including a link movable substantially in the direction of desired jaw movement and at one end engaging

said jaw, and at its opposite end provided with operating means having great mechanical advantage, and auxiliary clamping pressure imparting means cooperating with said link in effecting clamping but coacting with said jaw separately whereby a cumulative effect is attained, said latter means actuated through a portion of said first mentioned means.

12. In a clamping mechanism, a movable clamp jaw, an operating lever, a plurality of rods having different functions and performing their respective functions at different times and operatively connected to said jaw to draw the same towards closed position and by a separate operation thereafter to apply final clamping 15 pressure to said jaw, one rod effecting closing of the jaw and the other rod effecting final clamping thereof, a member to which said rods are connected at spaced points, and means forming a pivotal connection between said lever and 20 said member substantially in alinement with one of said rods.

13. In a clamping mechanism, a movable clamp jaw, a pivotal operating lever, a plurality of rods having different functions and performing their respective functions at different times and operatively connected to said jaw to draw the same towards closed position and by a separate operation thereafter to apply final clamping 25 pressure to said jaw, one rod effecting closing of the jaw and the other rod effecting final 30 clamping thereof, a member to which said rods are connected at spaced points, and means forming a pivotal connection between said lever and said member substantially in alinement with one 35 of said rods, the pivotal axis of said lever being closely adjacent the axial line of said rod.

14. In a clamping mechanism, a pivoted clamp jaw having adjacent its free end a slot, a pivoted operating rod for said jaw selectively positionable 40 by swinging movements in planes perpendicular to the planes of clamp jaw movement either outside the path of pivotal movement of said jaw or in said slot, said rod carrying means engageable with a surface of said jaw to apply force to move the latter towards closed position, and a connection at the other end of said rod for applying traction thereto including a pivoted lever pivotally connected to the rod for moving the latter towards a position perpendicular to the pivot of the lever, said rod and means being 45 releasable at will from said slot and cooperating relation with said jaw.

15. In a clamping mechanism, a pivoted clamp jaw having adjacent its free end a slot, a pivoted operating rod for said jaw selectively positionable 55 by swinging movements about an axis making a substantial angle with a line parallel to the jaw pivot axis either outside the path of pivotal movement of said jaw or in said slot, said rod carrying releasable cam means engageable with a surface of said jaw to apply force to move the latter towards closed position, and a connection at the other end of said rod for applying traction thereto including a 60 pivoted lever pivotally connected to the rod for moving the latter towards a position perpendicular to the pivot of the lever, said rod and cam means being releasable at will from said slot and cooperating relation with said jaw.

16. In a forging machine, a clamping device including a pivoted clamping member having a pivotal support at one end and a clamping die beneath said pivotal support and the other end thereof, and positioning and final force apply- 70 75

- ing means cooperating with the last mentioned end of said clamping member and each having a connection with the latter during clamping which permits swinging movement relative to the same and common final operating means for said positioning and final force applying means.
17. In a forging machine, a clamping device including a pivoted clamping member having a pivotal support at one end and a clamping die between said pivotal support and the other end thereof, and positioning and final force applying means each comprising tensioned link means individual thereto and cooperating with the last mentioned end of said clamping member and sequentially operable first to position said clamping die in substantially closed position and thereafter to effect clamping.
18. In a forging machine, a stationary clamping die, a pivoted clamping member carrying a clamping die arranged to cooperate in one position of said pivoted clamping member with said stationary die, and means for effecting closure of said clamping dies and for imparting a clamping pressure thereto including a member for moving said pivoted clamping member to closed position, a member connectible with said pivoted clamping member to transmit clamping pressure thereto, and means cooperating with said members whereby movement of said last recited member towards its working position causes said first mentioned moving member to move said pivoted clamping member to closed position.
19. In a forging machine, a stationary clamping die, a pivoted clamping member carrying a clamping die arranged to cooperate in one position of said pivoted clamping member with said stationary die, and means for effecting closure of said clamping dies and for imparting a clamping pressure thereto including a member for moving said pivoted clamping member to closed position, a member connectible with said pivoted clamping member to transmit clamping pressure thereto, and means cooperating with said members whereby movement of said last recited member towards its working position causes said first mentioned moving member to move said pivoted clamping member to closed position, said last mentioned means having provision for transmitting the final clamping force to the member connectible to the pivoted clamping member.
20. In a forging machine, a clamping member, a cooperating pivoted clamping member, means for initially positioning said pivoted clamping member adjacent said first mentioned clamping member, and distinct means for thereafter effecting clamping operation of said pivoted clamping member including link means, an operating lever, and connections between said link means and operating lever providing great mechanical advantage, said positioning means including an element actuated by said lever.
21. In a forging machine, a stationary clamping die, a cooperating pivoted clamping die, and a plurality of means for effecting clamping movement of said pivoted clamping die cooperating with the latter, one of said means providing a positioning movement and one applying final clamping force, and the latter means including a member engaging said pivoted die, an operating lever, and connections between said member and said operating lever having great mechanical advantage, said positioning means

including an element actuated through a portion of said connections.

22. In a forging machine, a clamping device including a movable clamp jaw, means for imparting a clamping pressure thereto having a bodily detachable connection therewith for releasing said means from said jaw at will, said means being normally released from said jaw during initial positioning of the latter, and means for initially positioning said jaw and including an element through which said clamping pressure imparting means is actuated.

23. In a clamping mechanism, a movable clamp jaw, an operating lever, a rod operatively connected to said jaw to initially move the same towards closed position, a second rod operatively connected to said jaw to impart to the latter a final clamping pressure, a member to which said rods are connected at spaced points, and means forming a pivotal connection between said lever and said member.

24. In a clamping mechanism, a movable clamp jaw, an operating lever, a rod operatively connected to said jaw to initially move the same towards closed position, a second rod operatively connected to said jaw to impart to the latter a final clamping pressure, a member to which said rods are connected at spaced points, and means forming a pivotal connection between said lever and said member substantially in alignment with one of said rods.

25. In a clamping mechanism, a movable clamp jaw, an operating lever, a rod operatively connected to said jaw to initially move the same towards closed position, a second rod operatively connected to said jaw to impart to the latter a final clamping pressure, a member to which said rods are connected at spaced points, and means forming a pivotal connection between said lever and said member substantially in alignment with one of said rods, the pivotal axis of said lever being closely adjacent the axial line of said last mentioned rod.

26. In a forging machine, a clamping member, a cooperating pivoted clamping member, and means for effecting clamping operation of said pivoted clamping member including means for transmitting a clamping force thereto cooperating therewith at a point spaced from its axis of pivotal movement and having a primary operating element, and cooperating clamp-operating means cooperating with and operated by said primary operating element of said first mentioned means.

27. In a forging machine, a stationary clamping die, a pivoted clamping member carrying a clamping die arranged to cooperate in one position of said pivoted clamping member with said stationary die, and means for effecting clamping movement of said pivoted clamping member cooperating with the latter at a point thereon at the opposite side of the clamping die carried thereby from the axis of pivotal movement and having a primary operating element, and cooperating clamp-operating means cooperating with and operated by said operating element of said first mentioned means.

28. In a forging machine, a clamping member, a cooperating pivoted clamping member, and means for effecting clamping operation of said pivoted clamping member including means for transmitting a clamping force thereto cooperating therewith at a point spaced from its axis of pivotal movement and having a foot treadle, and cooperating clamp-operating means

cooperating with and operated by said foot treadle of said first mentioned means.

29. In a forging machine, a stationary clamping die, a pivoted clamping member carrying a clamping die arranged to cooperate in one position of said pivoted clamping member with said stationary die, and means for effecting clamping movement of said pivoted clamping member cooperating with the latter at a point thereon at the opposite side of the clamping die carried thereby from the axis of pivotal movement, and having a foot treadle, and cooperating clamp-operating means cooperating with and operated by said foot treadle of said first mentioned means.
30. In a forging machine, a clamping member, a cooperating pivoted clamping member, means for effecting clamping operation of said pivoted clamping member including means for transmitting a clamping force thereto cooperating therewith at a point spaced from its axis of pivotal movement, and cooperating clamp-operating means associated with and operable by an element of said first mentioned means, said latter means being wholly released from said pivoted clamping member during complete opening of said pivoted clamping member.
31. In a forging machine, a stationary clamping die, a pivoted clamping member carrying a clamping die arranged to cooperate in one position of said pivoted clamping member with said stationary die, means for effecting clamping movement of said pivoted clamping member cooperating with the latter at a point thereon at

the opposite side of the clamping die carried thereby from the axis of pivotal movement, and cooperating clamp-operating means associated with and operable by an element of said first mentioned means, said latter means being wholly released from said pivoted clamping member during complete opening of said pivoted clamping member.

32. In a forging machine, a stationary clamping die, a pivoted clamping member carrying a clamping die arranged to cooperate in one position of said pivoted clamping member with said stationary die, and a plurality of means for effecting closure of said clamping dies and for imparting a clamping pressure thereto both cooperating with the pivoted clamping member at the opposite side of the clamping die thereon from the axis of pivotal movement, and common operating means for said closure effecting and clamping pressure imparting means.

33. In a forging machine, a clamping device including a pivoted clamping member having a pivotal support at one end and a clamping die between said pivotal support and the other end thereof, positioning means for said clamping member, final clamping force applying means for said clamping member, said positioning and final clamping force applying means cooperating with the last mentioned end of said clamping member, and common operating means for said positioning and final clamping force applying means.

WADE H. WINEMAN.
